TEE MEMBERS FOR SUSPENDED CEILINGS

Hugo E. Brandstetter, Chicago, and Vernon R. Beyer, Maywood, Ill., assignors to Alto Manufacturing Co., a corporation of Illinois

Application September 24, 1952, Serial No. 311,208

1 Claim. (Cl. 189—85)

This invention relates to inverted T-shaped supporting members and to T's for use in a grid system for suspended ceilings. The T's of the present invention have covers which fit over the arms of the T's. By using these covers, it is possible to fabricate, by a rolling process, highly efficient and attractive T members for use in a suspended grid system with attendant advantages heretofore unattainable in such systems.

Grid systems employing inverted T's of the present invention comprise a plurality of supporting T's which are suspended by wires or other suitable means from structural members or from an existing ceiling. The supporting T's are interlocked by a plurality of cross T's at spaced intervals. The cross T's are positioned at right angles relative to the supporting T's. The supporting T's and cross tees form a latticework and ceiling boards are placed within the lattice-work and rest on the arms of the T's to complete the ceiling installation.

In the past, certain of these T's for use in grid systems for suspended ceilings have been fabricated from extruded aluminum. These T's are quite expensive to produce and are difficult to fabricate. Furthermore, when assembling such aluminum members, no matter how clean the members are kept, a quantity of dirt is always present on the surface of the metal and when the unpainted aluminum T's are handled, this dirt comes off on the hands. In spite of extreme care in installing, some of this dirt is always transferred to the ceiling boards when they are inserted in place. The present invention provides a cover for the T's which is prefinished with a suitable decorative coating, such as paint, so that when the installation is made, the ceiling boards are kept clean.

With the system of the present invention, the supporting T's can be fabricated from cold rolled steel or similar material which is strong, thin, light and inexpensive. The T's are rolled into shape, rather than extruded, with consequent savings in manufacturing costs.

Prior to our invention, T's for use in grid systems for suspended ceilings could not be satisfactorily fabricated by rolling from a piece of sheet stock. Such a rolled T shape presents an unsightly gap at the junction of the so rolled arms and legs of the tee, which gap runs the entire length of the T and would be visible when the ceiling is installed. With the covered T of the present invention, the gap at the junction of the arms and legs of the T is hidden from view by the cover. This greatly improves the appearance of the installation and makes the use of a rolled shape commercially feasible.

When the system is installed, the cover is the only portion which is visible and consequently, only the cover need be finished. This further reduces costs. The cover may be pre-finished with any suitable decorative coating and the finish will not be disturbed during the ceiling installation since the cover need not be handled until shortly before the installation is completed.

A still further advantage inherent in the T's of our invention is the ease of fabrication. The means for securing the supporting T's and the cross T's together may

2

be provided at the same time that the T's are cut to length with resultant savings in manufacturing costs. Should it be necessary to extend the length of the supporting T's, this can be readily accomplished by the simple expedient of sliding a supporting T into the cover of an adjacent supporting T.

The structure by means of which the above and other advantages of the invention are attained will be described in detail in the following specification, taken in conjunction with the accompanying drawings, showing a preferred illustrative embodiment of the invention, in which:

Figure 1 is a perspective view of ceiling installation showing the manner in which the supporting T's and cross T's of the present invention are secured in place and showing how the ceiling boards are installed between the supporting T's and cross T's;

Fig. 2 is a perspective view showing a plurality of supporting T's and cross T's secured together;

Figure 3 is a perspective view of a portion of a supporting T and its associated cover;

Fig. 4 is a fragmentary perspective view of one end of a cross T;

Fig. 5 is a perspective view of a supporting T having a cross T secured thereto and showing how the ceiling board rests on an arm of the supporting T;

Fig. 6 is a cross sectional view taken along the lines 6—6 of Fig. 5;

Fig. 7 is a fragmentary top plan view, showing the manner of attaching a cross T to a supporting T;

Fig. 8 is a cross sectional view taken along the lines 8—8 of Fig. 7; and

Fig. 9 is a side elevational view, partially in section, showing the manner of securing two supporting T's together by sliding one supporting T into the cover of an adjacent supporting T.

Referring to the drawings which illustrate a suspended grid system employing the T's of the present invention, the system has a plurality of inverted T-shaped supporting T's 11 and cross T's 12. The cross T's are secured to the supporting T's at spaced intervals. Supporting T's 11 are suspended from structural members (not shown) or an existing ceiling (not shown) in any suitable manner, for example, by wires 13. The distances between supporting T's 11 and cross T's 12 may be varied rather widely as desired although in most installations the distances between two supporting T's 11 is approximately two feet and the distance between two cross T's 12 is usually approximately four feet to accommodate ceiling boards 14 of approximate 2' x 4' dimension. These dimensions are merely suggestive and are not to be taken as limitations upon the invention. The ceiling boards may be fabricated from any desirable material, suitably fibrous, which may be treated to render them fireproof. The boards may be formed of materials which are inherently fire-resistant. One such fibrous material is that sold by the Owens-Corning Fiberglas Corporation of Toledo, Ohio, under the trademark "Fiberglas."

Supporting T's 11 are rolled from a single piece of sheet stock to form an upstanding leg 15 of double thickness and arms 16 and 17 extending outwardly at substantially right angles from said leg. Each leg 15 is provided with holes 18 so that suspension wires 13 may be secured to the supporting T's.

When the T's are rolled, a gap or seam 21 is formed at the junction of leg 15 and arms 16 and 17, and the gap runs the length of the T. In the past, it was impractical to roll T's for suspended ceilings because of this unsightly gap which is visible when the T's were installed.

In our system, gap 21 is hidden from view by a cover having a body portion 22 and upwardly and inwardly extending flanges 23 at either end thereof. The cover

may be readily slid over **T 11** by sliding arms **16** and **17** under flanges **23** so that the cover body bridges arms **16** and **17** and hides gap **21**.

The cover also serves to join two supporting **T**'s together should it be necessary to increase the length of the supporting **T**'s where the installed ceiling is unusually long. Fig. 9 shows two supporting **T**'s **11** so joined, the arms of one **T** being securely held by the cover of the adjacent **T**. It is manifest that any number of supporting **T**'s may be joined in this manner.

At the time that supporting **T**'s **11** are cut to the desired length, ears **25** are alternately struck from arms **17** and **18** at appropriately spaced intervals. Ears **25** aid in securing cross **T**'s **12** to supporting **T**'s **11**.

Cross **T**'s **12** are also rolled from sheet stock and have a leg **26** and arms **27** and **28**. A gap **29** is present at the junction of leg **26** and arms **27** and **28**. A cover body **31**, having upwardly and inwardly extending flanges **32** which slide over arms **27** and **28**, is provided on each cross **T** **12** in a manner similar to that in which covers are provided on supporting **T**'s **11**.

Holes **33** are provided in ends of arms **27** and **28**. One hole **33** is provided in arm **27** at one end of cross **T** **12** (Fig. 5) and another hole **33** is provided in arm **28** at the other end of cross **T** **12** (Fig. 7). Holes **33** register with ears **25** and cross **T**'s **12** rest on and are secured to supporting **T**'s **11** by bending ears **25** downwardly into engagement with arm **27** or arm **28** as is clearly shown in Figs. 5-8. We prefer to provide one ear **25** and one associated hole **33** for securing each end of cross **T** **12** to a supporting **T** **11**. By providing only one hole and one ear, it is impossible to improperly attach the cross **T**'s to the supporting **T**'s.

When attached to supporting **T** **11**, arms **27** and **28** of cross **T** **12** overlie flange **23** and arm **16** or **17** of the supporting **T**. So that the bottom of cover body **31** will be flush with the bottom of cover body **22**, it is preferred to offset the ends of arms **27** and **28**, as indicated at **34**. Instead of offsetting the ends of arms **27** and **28**, covers **22** and **31** may be made flush by making cover body **31** thicker than cover body **22**, or flanges **32** could be bent upwardly a sufficient distance, before bending them inwardly, to compensate for the thickness of the metal of flange **23**.

To install the **T**'s of our invention into a grid system, supporting **T**'s **11** are cut to length. Ears **25** may be struck in arms **16** and **17** at the same time that the **T**'s are cut to length. Covers are then slid on supporting **T**'s **11** and the supporting **T**'s are suspended from the ceiling or structural members by wires or other suitable means. The supporting **T**'s may be secured to the walls of the

room by resting the arms of the **T**'s on the horizontal flange of an L-shaped molding **35**.

Cross **T**'s **12**, having their associated covers in place, are then placed between the supporting **T**'s **11** with ears **25** in register with holes **33**. Ears **25** are then bent downwardly to securely lock the cross **T**'s to the supporting **T**'s. Ceiling boards **14** are then set into place, the ends of the boards resting on the arms of the cross **T**'s and supporting **T**'s.

While we have described a preferred embodiment of our invention in considerable detail, it is to be understood that the description is intended to be illustrative rather than restrictive as many details may be modified without departing from the spirit or scope of the invention. Accordingly, we do not intend to be restricted to the specific structure described except as limited by the appended claim.

We claim:

A grid system adapted to be suspended from an existing structure comprising a plurality of supporting **T**'s, each of said supporting **T**'s having a leg and arms, means in said legs for suspending said supporting **T**'s from said structure, ears in said supporting **T** arms, a plurality of cross **T**'s, each of said cross **T**'s having a leg and arms, said cross **T** arms having an aperture therein, a cover on each of said supporting **T**'s covering the entire length of each of said supporting **T**'s, each of said supporting **T** covers having a body portion and a pair of upwardly and inwardly extending flanges adapted to slidably fit over and bridge the arms of said supporting **T**, a cover on each of said cross **T**'s covering substantially the entire length of each of said cross **T**'s, each of said cross **T** covers having a body portion and a pair of upwardly and inwardly extending flanges adapted to slidably fit over and bridge the arms of said cross **T**, the arms of each of said cross **T**'s being offset at their ends whereby the arms at each end of each of said cross **T**'s may be positioned on an associated supporting **T** with said aperture in said cross **T** arm in register with an associated ear in said supporting **T** arm, said cross **T** cover being flush with said supporting **T** cover.
